UNITED STATES PATENT OFFICE.

GEORGE H. HILL, OF SCHENECTADY, NEW YORK, ASSIGNOR TO GENERAL ELECTRIC COMPANY, A CORPORATION OF NEW YORK.

PROTECTIVE DEVICE FOR TELEPHONE-CIRCUITS.

1,267,223.

Specification of Letters Patent. Patented May 21, 1918.

Application filed November 13, 1915. Serial No. 61,230.

To all whom it may concern:

Be it known that I, GEORGE H. HILL, a citizen of the United States, residing at Schenectady, county of Schenectady, State 5 of New York, have invented certain new and useful Improvements in Protective Devices for Telephone-Circuits, of which the following is a specification.

This invention relates to protective devices 10 for telephone circuits, and its object is to prevent the occurrence of accidents due to the crossing of telephone lines by conductors carrying a potential that is dangerous to human life. The practice of using telephone 15 lines for train despatching purposes is quite general and on the increase. The telephone lines are built along the railroad right of way and are frequently supported on the same poles as the high tension transmission lines. 20 Where they are not on the high tension transmission poles, they will be found on the overhead trolley poles, which even in the case of direct current, if of 1200 volts or over, presents dangerous possibilities. 25 It is customary to bring out telephone jacks from the despatching wires at frequent intervals along the right of way, so that conductors can plug their portable telephones into the despatching circuit. It is 30 clearly impossible actually to prevent or avoid possibility of crosses between high tension circuits and the telephone wires where long parallels exist like the cases above mentioned. It becomes desirable, therefore, to 35 protect the telephone circuit thoroughly in case such crosses do occur.

My invention aims to accomplish this result by providing a device which will automatically ground the telephone wires and 40 will also interpose a positive barrier at the entrance to the telephone jack so that the telephone plug cannot be inserted. A visual signal may also be given, warning the conductor not to attempt to plug in.

45 The accompanying drawing is a diagrammatic illustration of one form of my invention.

The telephone wires 1 are parallel with and below the high tension transmission 50 conductors 2. Branch wires 3 lead from the telephone circuit into the box 4 where they connect with a telephone jack 5. In the wall of the box is an opening 6 through

which the conductor or other employee can insert the plug 7 of his portable telephone. 55

Pivoted at 8 inside of the box is a heavy arm 9 grounded at 10 and carrying a shutter 11 which is adapted to close the opening 6 and obstruct the entrance of the plug 7. The arm is normally held in a raised position, 60 with the shutter out of line with the opening 6, by means which will respond to an abnormally high potential only. I prefer the arrangement shown, in which the arm is suspended by a fuse wire 12 connected to 65 a spark terminal 13. Adjacent to this terminal are two other spark terminals 14, 15 connected respectively with the two sides of the telephone circuit. On the arm is a contact plate 16 adapted to coöperate with 70 contacts 17 on the branch wires from the telephone circuit.

The operation is as follows: The spark gap is set to remain inactive at ordinary telephone voltages, but to spark over at any 75 voltage which may be dangerous. In case a light cross occurs between the telephone line and a high potential wire, the spark gaps will arc over and thus ground the telephone wires. If the cross is maintained and the 80 voltage imparted to the telephone wires is sufficient, a considerable amount of energy will pass through the fuse wire and in time it will melt and permit the heavy arm 9 to drop by gravity. Obviously, the time required to effect this result will depend upon the voltage impressed, and the size of the fuse. When the arm drops, the contact plate 16 closes upon the contacts 17 and makes a solid ground for the telephone 85 wires. At the same time, the shutter on the arm passes down in front of the jack and obstructs the opening 6, so that a telephone plug cannot be inserted. The shutter will be plainly visible through the opening, so that 90 a visual warning is thus given of the abnormal condition of the line. If desired, the shutter can be painted red, to emphasize the warning.

What I claim as new and desire to secure 100 by Letters Patent of the United States, is,—

1. The combination with a telephone line, of a jack connected thereto, and means for automatically grounding said line and obstructing said jack when a dangerous voltage is impressed on said line.

2. The combination with a telephone line, of a jack connected thereto, a movable member for grounding said line and obstructing said jack, a fuse keeping said member **in** operative, and a spark gap in circuit with said fuse.
3. The combination with a telephone line, of a jack connected thereto, a shutter adapted to obstruct said jack, and means responsive to a dangerous voltage on said line for causing said shutter to move in front of said jack.
4. The combination with a telephone line, of a jack connected thereto, a member mounted adjacent to said jack and arranged

to obstruct the same, a fuse holding said member out of obstructing position, and a spark gap in circuit with said fuse.

5. The combination with a telephone line, of a jack connected thereto, a grounded arm pivoted adjacent to said jack and provided with means for obstructing said jack, a fuse holding said arm in inoperative position with reference to said jack, a spark gap in circuit with said fuse, and contacts for short circuiting the jack when the fuse melts and the arm moves to operative position.

In witness whereof I have hereunto set my hand this 11th day of November, 1915.

GEORGE H. HILL.
